UNITED STATES PATENT OFFICE.

WILLIAM H. MILLIKEN, JR., OF BROOKLYN, NEW YORK, ASSIGNEE TO BINNEY & SMITH CO., OF NEW YORK, N. Y., A CORPORATION OF NEW JERSEY.

PAINT BOX.

Application filed February 20, 1923. Serial No. 620,153.

To all whom it may concern:

Be it known that I, WILLIAM H. MILLIKEN, Jr., a citizen of the United States, and resident of Brooklyn, in the county of Kings and State of New York, have invented certain new and useful Improvements in Paint Boxes, of which the following is a specification.

This invention is an improved paint box of the general character commonly used by artists, and including a plurality of pans or compartments for the several colors, and a separate compartment for the brush or brushes.

In my improved construction the small paint pans are carried by the top wall of a sheet metal tray which is supported within the box by side walls resting on the bottom of the box. The brush compartment is arranged alongside of the tray and the body of the box is provided with a hinged cover.

The main object of my invention is to provide a simple form of brush support which will not add materially to the cost of the box, which will so position the brush that it will not rattle on moving the box, which will hold the brush so that it may be easily picked up when the box is open, and which will position the tray so that it cannot move laterally in the box.

As one important feature of my construction, the brush support is so positioned that it engages with the brush at a point adjacent to the bristles and the cover cooperates with the support and also prevent endwise movement of the brush on the support. Thus the bristles are protected in case the box should be carried in the pocket with the bristle end of the brush extending downwardly.

Other objects and advantages will be pointed out hereinafter, or will be apparent from a consideration of the specific constructions illustrated.

In the accompanying drawing:

Fig. 1 is a top plan view of a paint box embodying my invention, the cover being open.

Fig. 2 is a transverse section on the line 2—2 of Fig. 1, the cover of the box being closed.

Fig. 3 is a perspective view of a portion of the color tray and brush support integral with the latter.

Fig. 4 is a section through the brush sup-

port and taken lengthwise of the box substantially on the line 4—4 of Fig. 2.

Fig. 5 is a plan view of a portion of a box showing a modified form of brush support, and

Fig. 6 is a transverse section on the line 6—6 of Fig. 5.

I have illustrated my invention in connection with a paint box including a body portion or box proper having a bottom wall 10 and peripheral walls 11 integral therewith, the upper edge of the rear wall being connected to a cover 12 by a hinge 13. The paint is carried in a plurality of trays 14 which are preferably formed of sheet metal and are held friction tight in apertures in the top wall 15 of a tray removably supported within the box. This tray is formed of sheet metal and the top wall 15 is supported above the bottom of the box by depending peripheral walls 16. The tray is preferably of a length substantially equal to the length of the box but is made materially narrower than the box so as to leave a compartment or chamber 17 for the brush or brushes.

The box and trays may be made of such width that there may be two of the trays extending lengthwise of the box and spaced apart to leave a brush compartment therebetween, or there may be a single tray with the brush compartment along one side thereof, as shown in the drawing.

As one important feature of my invention I provide a brush support which will not only support the brush and permit it to be easily picked up and keep it from rattling about in the brush compartment, but which will also serve to hold the tray or trays against lateral movement in the box.

In the form of brush support shown in Figs. 1 to 4 inclusive a portion of one side wall 16 of the tray is bent out to form a partition 18 extending transversely of the compartment 17 and having a terminal flange portion 19 adapted to engage with or rest against the wall 11 of the box. Thus the partition 18 is of a length equal to the width of the brush compartment 17 and holds the tray against lateral movement. The cover of the box is provided with a plurality of depending ridges or beads 20 extending transversely thereof so as to divide the top wall into a series of shallow

pans 21 which may be used for mixing paints. The partition 18 which constitutes the brush support is so positioned lengthwise of the box that it registers with one of the depending ridges or beads of the cover. The upper edge of the partition 18 is provided with one or more notches or recesses to receive the brush, and the brush when in place is held in the notch or recess by the ridge 20 of the cover. It will be noted that as the brush support is formed by one wall of the paint pan carrying tray there are no additional parts or pieces required, and nothing which can get lost or out of place, and there is no additional weight and no material addition to the expense of manufacture.

In some constructions it may be advisable to form the brush support separate from 20 rather than integral with the wall of the tray. Such a construction is illustrated in Figs. 5 and 6 in which the brush support is in the form of a sheet metal strip 22 which has one end portion 23 bent to form 25 a spring clamping portion to receive and grip the depending edge 16 of the tray. The other end 24 may be bent to lie against the front wall of the box. The strip may be bent to provide a series of notches or 30 recesses to receive the brush, and the brush support is preferably so positioned as to register with one of the depending beads or ridges 20 of the cover. This form of strip may act resiliently against the front 35 wall of the box so as to exert a pressure tending to hold the tray against the opposite side of the box.

Having thus described my invention what I claim as new and desire to secure by Letters Patent is:

1. A paint box having a hinged cover, a tray within said box and having a top wall provided with apertures, color pans mounted within said apertures, said tray having depending side walls for supporting said top wall and one of said side walls being substantially parallel to and spaced from the side walls of the box to form a brush receiving compartment, and a brush support extending from said tray wall to said box wall to hold said walls in spaced relationship, said support having a recess in the upper side thereof to receive a brush and said box cover having a depending ridge 45 extending transversely of the upper surface and spaced from the end of the box to register with the brush support and retain

the brush in said recess when the cover is closed.

2. A paint box having a color carrying tray therein presenting a side wall substantially parallel to and spaced from a side wall of the box to form a brush receiving compartment, and a brush support extending from said tray wall to said box wall at a point spaced from the end of the box, said support having a recess in the upper side thereof to receive a brush, and a box cover having a portion adapted to register with the brush support and retain the brush in said recess when the cover is closed.

3. A paint box having a tray extending lengthwise thereof and spaced from one side to form a brush compartment, and a brush support in said compartment and spaced 75 from the end of the box to a distance greater than the length of the bristles of the brush, and serving to hold the tray against lateral movement, said box having a cover provided with a portion adapted to engage 80 with the brush to hold the latter against endwise movement in the compartment.

4. A paint box having a color carrying tray and a brush compartment extending lengthwise thereof, a brush support in said compartment and spaced from one end of the box to hold one end of the brush out of engagement with the bottom of the box, and a cover for the box provided with a portion adapted to engage with the brush 90 and cooperate with the support to hold the brush against endwise movement in the compartment.

5. A paint box having a color carrying tray extending lengthwise thereof and presenting a side wall spaced from a side wall of the box to form a brush compartment, and a portion of the side wall of said tray being bent to extend transversely of said compartment at a point spaced from the 100 end of the box and serves as a brush support, and provided with a notch in its upper edge to receive a portion of the brush adjacent to the bristles, and a cover for the box adapted to engage with the brush and 105 cooperate with the support to prevent endwise movement of the brush and prevent contact of the end of the bristles with the end of the box.

Signed at New York, in the county of 110 New York and State of New York, this 19th day of February, A. D. 1923.

WILLIAM H. MILLIKEN, JR.
